[57] CLAIM

The ornamental design for a spiked feeding wheel for use in a board splitting apparatus, as shown and described.

DESCRIPTION

FIG. 1 front elevational view of a spiked feeding wheel for use in a board splitting apparatus showing my new design;
FIG. 2 is a left side elevational view;
FIG. 3 is a right side elevational view;
FIG. 4 is a top plan view;
FIG. 5 is a bottom plan view;
FIG. 6 is a rear elevational view;
FIG. 7 is a vertical cross-sectional view taken along line 7—7 of FIG. 1;
FIG. 8 is a perspective view;
FIG. 9 is a cross-sectional view taken along lines 9—9 of FIG. 1;
FIG. 10 is a cross-sectional view taken along line 10—10 of FIG. 1;
FIG. 11 is a second embodiment of a front elevational view of a spiked feeding wheel for use in a board splitting apparatus showing my new design;
FIG. 12 is a left side elevational view;
FIG. 13 is a right side elevational view;
FIG. 14 is a top plan view;
FIG. 15 is a bottom plan view;
FIG. 16 is a rear elevational view;
FIG. 17 is a vertical cross-sectional view taken along line 17—17 of FIG. 11;
FIG. 18 is a perspective view;
FIG. 19 is a cross-sectional view taken along lines 19—19 of FIG. 11; and,
FIG. 20 is a cross-sectional view taken along line 20—20 of FIG. 11 thereof.
